UNITED STATES PATENT OFFICE.

HARRY MIKKELSEN, OF CHICAGO, ILLINOIS, ASSIGNOR TO UNDERWOOD TYPEWRITER COMPANY, OF NEW YORK, N. Y., A CORPORATION OF DELAWARE.

TYPE-WRITING MACHINE.

1,150,287.

Specification of Letters Patent. Patented Aug. 17, 1915.

Application filed December 4, 1913. Serial No. 804,595.

To all whom it may concern:

Be it known that I, HARRY MIKKELSEN, a citizen of the United States, residing in Chicago, in the county of Cook and State of Illinois, have invented certain new and useful Improvements in Type-Writing Machines, of which the following is a specification.

This invention relates to collating boards provided upon the paper carriages of type-writing machines having revoluble platens. It is customary to collate the work-sheets in various relative positions upon the board, and after such collating, to carry the sheets from the board around the platen to the printing position, without disturbing the relative arrangement of the sheets.

One of the objects of the present invention is to improve the means for carrying the collated sheets around the platen and maintaining them in their proper relationship. To this end, I provide at the ends of the platen flexible endless bands, each of which has a series of sheet-impaling studs, and each of which also has a series of holes to fit studs or sprockets on the platen itself. By this means, the bands are caused to travel in unison, and moreover any liability of the bands slipping or creeping edgewise upon the platen is avoided by their engagement with the platen studs or sprockets. The other ends of the endless bands run over an idle roll, which may also be provided with sprockets to prevent edgewise creeping of either band at this point; it being desirable to maintain the bands with the impaling studs thereon in exact relationship to each other at all times. The bands are kept taut independently of each other by springs, one at each end of the idle roll over which the bands run.

Another feature of the invention resides in the means for attaching the board-supporting frame to a supplemental carriage. The arms which extend down from the board-supporting frame are made extensible and connected by universal joints to plates, and the plates are fixed to the supplemental carriage. By reason of the extensibility of the arms and the adjustability of the plates, necessity of accurate and careful manufacture and fitting is avoided.

Another feature of the invention is the provision of a wire or thin support upon which to hang the carbon sheets. This wire

extends across from one of the stud-bands to the other, and travels with the bands around the platen. The carbon sheets are folded and are hung upon this cross wire, which is of great convenience when adjusting the sheets, and especially when removing some of the work-sheets and replacing them by others.

Other features and advantages will hereinafter appear.

In the accompanying drawings, Figure 1 is a front perspective view of a part of a paper carriage of an Underwood front-strike typewriting machine, showing the sheet board applied thereto and illustrating my improvements. Fig. 2 is a sectional view to illustrate the universal joint for attaching the sheet board to the supplemental carriage. Fig. 3 is a sectional side elevation of an Underwood typewriter carriage with my improvements applied thereto. Fig. 4 is a front elevation to illustrate the connection of the collating device to the typewriter carriage.

Type-bars 1 strike against the front side of a cylindrical platen 2, which is revolubly mounted by means of an axle 3 in a carriage 4, which is propelled by a spring (not shown) in the usual manner and controlled by the usual escapement mechanism, which is operated by the keys that actuate the type-bars 1, as is well known.

The sheets to be collated are laid upon a board 5, which may extend upwardly and rearwardly from the platen; the side margins of the sheets overlying endless flexible thin metal bands 6, one at each end of the platen 2; the bands looping around the platen and extending up along the collating board, and at their upper portions running over an idle roll or pulley 7. The perforations in the side margins of the work-sheets engage studs 8, which are arranged in rows on the opposite bands 6, preferably along their inner edges. The bands may be separated so as to expose sufficient space on the platen between them to form the desired writing surface, although the bands may, if desired, be of very thin metal and hug closely to the platen, and themselves afford a suitable backing for the paper to receive the type impressions.

The studs 8 in one band must bear a fixed relationship to the studs 8 on the other band; and in order to preserve this relation-

ship, the platen is provided at its ends with studs or sprockets 9, which fit into perforations 10, each band having a line of these perforations extending for its entire length, 5 preferably along its outer edge. Both sets of studs or sprockets 9 being fixed to the platen, it follows that one band 6 must travel synchronously with the other, and hence the relationship between the impaling studs 8 10 on one band and those on the other band is always preserved. Said sprockets 9 also may fit so closely in the holes 10 of the band as to prevent sidewise creeping of the latter along the platen; and, if desired, the idle 15 roll 7 may also be provided with similar sprockets 11 for the same purpose.

The collating board 5, which supports the flexible bands 6 and serves as a table on which to collate the sheets, may be supported 20 by upper and lower cross bars 12, 13, which are bent down at their opposite ends at 14 and connected by rods 15 which extend upwardly and rearwardly from the typewriter carriage 4, being connected thereto at their 25 lower ends by screws 16.

The idle roll 7 may be carried upon extensions or rods 18, which telescope into the ends of the rods 15, and are constantly pressed outward by springs 18^a, so as to keep 30 a tension on the stud bands 6.

From the rods 15 extend rearwardly arms 19 to a carriage 20, which may be in the form of a grooved slide, running on balls carried by upper and lower tracks 21, 22, 35 which are held by brackets 23, carried upon arms 24 extending upwardly and rearwardly from the typewriter framing 24^a. The arms 19 may be sufficiently separated to permit the bands 6 to pass between them. Each 40 arm 19 may be composed of two portions, one of them, 25, telescoping into the other, and carrying at its rear end a ball 26, which forms part of a ball-and-socket joint; the other part thereof being carried upon a 45 plate 27, which is attached by screws 28 to the supplementary carriage 20. The extensible part 25 of the arm 19 may be secured by a set screw 29, Fig. 1. The extensible support 25 permits truing of the sheet board 50 relatively to the platen, and the universal joint at 26 permits the plate 27 to be turned to fit the front surface of the carriage 20, notwithstanding the shifting or adjustment of the part 25 relatively to 19. The rods or 55 extensions 18 may also be joined at their upper ends by a cross bar 17. The rods 18 may also carry an apron 30 to guide the sheets around the idle roll 7 and down behind the collating board, to the usual guide- 60 plate or paper shelf 31, which conducts the sheets beneath and up in front of the platen to the printing point.

A support 32 upon which to hang carbon sheets, is herein shown as a wire or rod extending across from one to the other of the 65

stud-bands 6, and attached to the bands by means of blocks having openings to receive the ends of the wire, the said blocks being fixed to the bands and provided with set screws to secure the rod. 70

Variations may be resorted to within the scope of the invention, and portions of the improvements may be used without others.

Having thus described my invention, I 75

claim:

1. The combination with a carriage and a revoluble platen thereon, of a sheet-collating-board extending away from the platen, rods mounted upon the carriage and extending away from the platen and supporting said sheet-collating-board, extensions telescoped within said rods, springs pressing said extensions outwardly, sheet-carrying bands running upon the platen, and means carried by said rods to be engaged by said bands, 85 whereby the bands are held taut.

2. The combination with a carriage and a revoluble platen thereon, of a sheet-collating-board extending away from the platen, rods mounted upon the carriage and extending 90 away from the platen and supporting said sheet-collating-board, extensions telescoped within said rods, springs pressing said extensions outwardly, sheet-carrying bands running around the platen, revoluble means 95 carried by said rods over which said bands run, and whereby the bands are held taut, and a sheet deflector carried by said extensions.

3. The combination with a carriage and a 100 revoluble platen thereon, of a sheet-collating-board extending upwardly and rearwardly from the platen, sheet-carrying devices extending from said platen along said board, a supplementary carriage, tracks therefor, 105 and supports extending from said sheet-collating-board structure to said supplementary carriage and including extensible arms to permit the board to be trued or adjusted 110 relatively to the platen.

4. The combination with a carriage and a revoluble platen thereon, of a sheet-collating-board extending upwardly and rearwardly from the platen, sheet-carrying devices extending from said platen along said board, 115 a supplementary carriage, tracks therefor, and supports extending from said sheet-collating-board structure to said supplementary carriage and including extensible arms to permit the board to be trued or adjusted 120 relatively to the platen; said arms connected to said supplementary carriage by universal joints.

5. The combination with a carriage and a 125 revoluble platen thereon, of a sheet-collating-board extending away from the platen, rods mounted upon the carriage and extending away from the platen and supporting said sheet-collating-board, extensions telescoped within said rods, springs pressing said ex- 130

tensions outwardly, sheet - carrying bands running around the platen, revolute means carried by said rods over which said bands run, and whereby the bands are held taut, 5 and a device carried by said extensions to deflect the sheets around said revolute means and down back of the sheet-collating-board.

6. The combination with a carriage and a 10 revolute platen thereon, of a sheet-collating-board extending away from the platen, rods mounted upon the carriage and extending away from the platen and supporting said sheet-collating-board, extensions telescoped 15 within said rods, springs pressing said extensions outwardly, sheet - carrying bands running around the platen, revolute means carried by said rods over which said bands run, and whereby the bands are held taut, a 20 device carried by said extensions to deflect the sheets around said revolute means and down back of the sheet-collating-board, and a paper guiding shelf or plate on the carriage to receive the sheets from said deflector and conduct them forwardly around the under side of the platen.

7. The combination with a revolute platen and a sheet-collating board extending obliquely upward therefrom, of flexible 30 bands extending from the ends of the platen along said sheet-collating board, and each having studs to engage perforations in the side margins of the work-sheets, said studs on one band having a fixed relation or registry with the said studs on the other band, and studs or sprockets secured upon the ends of the platen; said bands having perforations or means to engage said platen studs or sprockets and cause the bands to move 35 in unison and hold the sheet-engaging studs on one band in register with the sheet-engaging studs on the other band.

8. The combination with a revolute platen and a sheet-collating board extending 45 obliquely upward therefrom, of flexible bands extending from the ends of the platen along said sheet-collating board, and each having studs to engage perforations in the side margins of the work-sheets, said studs on one band having a fixed relation or registry with the said studs on the other band, and studs or sprockets secured upon the ends of the platen; said bands having perforations or means to engage said platen studs 50 or sprockets, and cause the bands to move in unison and hold the sheet-engaging studs on one band in register with the sheet-engaging studs on the other band; said perforations being arranged along the outer edges of the bands, and said sheet-engaging studs being arranged along the inner edges or margins of the bands.

9. The combination with a revolute platen and a sheet-collating board extending 65 obliquely upward therefrom, of flexible

bands extending from the ends of the platen along said sheet-collating board, and each having studs to engage perforations in the side margins of the work-sheets, said studs on one band having a fixed relation or registry with the said studs on the other band, 70 studs or sprockets secured upon the ends of the platen; said bands having perforations or means to engage said platen studs or sprockets, and cause the bands to move in unison and hold the sheet-engaging studs on one band in register with the sheet-engaging studs on the other band; said perforations being arranged along the outer edges of the bands, and said sheet-engaging 75 studs being arranged along the inner edges or margins of the bands, and an idle roll over which said bands run, said idle roll also having sprockets to engage said perforations to prevent edgewise creeping of the 80 bands.

10. The combination with a revolute platen and a sheet-collating board extending therefrom, of flexible bands extending from the ends of the platen along said sheet-collating board, said bands running over the ends of the platen and each having studs to engage perforations in the margins of work-sheets, the studs on one band having a fixed relation or registry with the studs 95 on the other band, and inter-engaging means on said bands and platen forming a positive means to maintain the studs on one band in register with the studs on the other band; said inter-engaging means also serving as a means to prevent creeping or movement of the bands relatively to the platen in a direction longitudinally of the platen.

11. The combination with a revolute platen and a sheet-collating board extending therefrom, of flexible bands extending from the ends of the platen along said sheet-collating board, said bands running over the ends of the platen and each having studs to engage perforations in the margins of work-sheets, the studs on one band having a fixed relation or registry with the studs on the other band, inter-engaging means on said bands and platen forming a positive means to maintain the studs on one band in register with the studs on the other band; said inter-engaging means also serving as a means to prevent creeping or movement of the bands relatively to the platen in a direction longitudinally of the platen, and a 100 guide roll at the end of the collating board remote from the platen and over which the work-sheets are carried by said bands, said roll provided with means coöperating with said means on the bands to prevent creeping 105 or displacement of the bands along said roll in the direction of its length.

12. The combination with a revolute platen, of thin flexible endless bands running over the ends of the platen and hav- 110 115 120 125 130

4

ing leads extending upwardly and rearwardly from the platen, a guiding roll at the outer ends of said leads and over which the bands run, said bands each having studs to engage perforations in the side margins of work-sheets, the studs on one band being arranged in a fixed relation or registry with the studs on the other band, said bands and the platen having coöperating means forming a positive driving connection between the platen and said bands for causing the latter to move in unison and maintain the studs on one band in register with those on the other band, and means forming a yielding support for said guiding roll and maintaining said bands taut.

13. The combination with a carriage and a revoluble platen thereon, of a sheet-collating board extending upwardly and rearwardly from the platen, flexible bands extending from the ends of the platen along said sheet-collating board, each band having studs to engage perforations in the side margins of work-sheets, and a rod or support extending transversely from one band 20 to the other and connected to said bands, 25 said support forming a means upon which folded carbon sheets may be hung.
